WATER HEATER WITH SAFETY DRAIN

Morris Yavitch, Los Angeles, Calif.

Application March 24, 1941, Serial No. 384,915

1 Claim. (Cl. 122—13)

This invention relates to water heaters and particularly to that type of heater in which the water is heated in a boiler having a relatively large capacity, said boiler being surrounded with a jacket which is spaced therefrom, with insulating material packed in the space therebetween. The boiler is usually provided with a blow-off or safety valve from which a drain-pipe leads downwardly toward the heater support. Further, a valved outlet is provided at or near the bottom of the boiler through which the latter may be drained, and the valve casing has means for attaching a hose or other piped connection for carrying away the water as it escapes. It is to be understood that such heaters are well known and form no part of my invention except as they are associated with the safety-drain. While, as stated, this drain is particularly adapted for use with the type of heater above referred to, it is not confined to that type and it is to be understood that the claim hereto appended is not intended to be limited to that type.

The drain itself consists of an open-topped tray or sink-like member which is so placed below the heater and is so extended on all sides as to catch all the water which may escape or be released from the heater, and of a drainage pipe or connection which leads from the bottom part of the tray to an outside sewer, sump, or other out-of-the-way disposal place and is thus prevented from reaching the floor or other support upon which the heater stands. As is apparent, if the water so escaping reaches the floor or support it will spread to the carpets or rugs and do great damage. Further, if the heater be on an upper floor, the water will leak or run down to the lower floor or floors and do great damage there. In apartment houses, for example, where heaters are used on the several floors, the drainage pipes from the trays may be connected to a common conduit which leads outside the building to a suitable place of disposal.

When the drainage tray is installed with the heater, it is preferably rigidly attached to and forms a part thereof. In case it is added to a heater which is already in use, it is preferably left unattached to the latter but is simply placed beneath the heater, the legs of the old heater resting within the tray.

In the accompanying drawing, Fig. 1 is mainly a side elevation of a heater having the safety drainage tray rigidly attached and forming part of the heater, certain parts being shown in section for clearer illustration; Fig. 2 shows, on a smaller scale, a pair of heaters on two floors of

a building, the trays being connected to a common drainage pipe, and Fig. 3 shows the tray unattached to the heater, the latter simply standing within the tray, the lower part only of the heater appearing and the tray being shown in section.

Taking up, first, the structure shown in Fig. 1, 10 represents the boiler of the heater, the same being encased within a jacket 11, which is usually a cylindrical sheet-metal member. It extends both above and below the boiler, is closed at the top and open at the bottom, and is provided with the usual door 12, through which access may be had to the burner, not shown. This burner has a flue 13 which extends upwardly through the boiler and has within it a spiral member 14 for deflecting the air passing up the flue outwardly against the latter thus to cause the gases to impart their heat to the water in the boiler. Surrounding the boiler and within the jacket is a body of insulating material 15, for a purpose well understood. Within a casing 16 is a safety valve which automatically opens if and when the pressure within the boiler becomes excessive. Any water or steam then passing through the valve is conducted downwardly through a pipe 17. Further, the boiler is provided with a valve 18 to control a passage through which the water in the boiler may be drained. Preferably, and as shown, the casing of this valve has a short pipe 19 connected therewith. The pipes 17 and 19 preferably extend farther down than the jacket 11.

The heater is supported upon legs 20 which are attached, as by bolts 21, to the lower part of the jacket 11. Supported upon said legs, as by bolts 22, is an open-topped tray or sink-like member 23. As shown, the legs 20 are bent outwardly between the jacket and the tray so that the outer flanged rim of the tray will extend on all sides beyond the jacket and beyond the lower ends of the pipes 17 and 19. As thus constructed and arranged, any leakage occasioned by a cracked boiler will be directed downwardly by the jacket and will drip from its lower rim into the tray. In the same way, any water flowing through the pipes 17 and 19 will enter the tray. Thus, all the water which escapes from the boiler whether through a crack therein or through the said pipes is caught within the tray and is prevented from reaching the floor. As noted, the bent portion 24 of the legs has its upper surface inclined downwardly and inwardly so that any drippings from the jacket falling on said surface will be drained into the tray. The tray may be round in contour or of any other desired shape. Further, the legs, jacket and tray may be secured to-

gether by welding or in any other suitable way, or the tray and legs may be cast or otherwise formed in one integral piece.

Opening into the tray at its lowermost point is a passage 25, within which is attached a drain pipe 26. This pipe leads to a sewer connection or to any other place where the water may run to waste.

In Fig. 2, there is shown one of the heaters of Fig. 1 supported upon a floor 27 and, above it, another floor is indicated at 28 upon which another heater, shown in part only, is supported. The drain pipes 26 of the trays 23 are connected with a riser pipe 29 which may discharge into any suitable receptacle. This pipe 29 may be located inside the wall 30 or outside the wall, as shown.

Fig. 3 shows the lower part of the jacket 11 of a heater and the ends of the pipe 17 and 19. These parts are the same as the corresponding parts in Fig. 1. The heater is supported upon legs 31 which, in this case, rest upon and within the tray 23a. The tray itself may rest upon any

suitable supports, as upon legs 32 which may extend to the floor, as indicated.

Having thus described my invention, I claim:

A water heater of that type which has a surrounding jacket, the jacket having an open lower end which is lower than the boiler, a plurality of legs attached to the jacket, and a support upon which said legs rest, the combination with said heater of an open topped tray having its sides attached to the said legs, the legs being bent outwardly between the jacket and the said support so that the tray is extended in all lateral directions beyond the lower end of the jacket so that any water which escapes from the boiler through a crack therein will be directed downwardly by the jacket and will be caught in said tray, the said upper surface of the bent portions of the legs being inclined downwardly and inwardly whereby any water which falls on said surface is caused to flow into the tray, and a drainage pipe attached to said tray through which the water therein is conducted to waste.

MORRIS YAVITCH.
